T. W. BRITTAI^N

OIL WELL PUMP

Filed June 21, 1924

UNITED STATES PATENT OFFICE.

THOMAS W. BRITTAINE, OF LONG BEACH, CALIFORNIA.

OIL-WELL PUMP.

Application filed June 21, 1924. Serial No. 721,418.

To all whom it may concern:

Be it known that I, THOMAS W. BRITTAINE, a citizen of the United States, residing at Long Beach, in the county of Los Angeles, 5 State of California, have invented a new and useful Oil-Well Pump, of which the following is a specification.

This invention relates to pumps for lifting fluid from a deep well and refers particularly to the type of reciprocating pumps employed in pumping oil from deep oil wells.

The present type of deep well pumps employed upon oil wells are extremely unsatisfactory and inefficient. Despite the 15 presence in numerous wells of considerable quantity of oil, the present type of pumping apparatus is enabled, only spasmodically to remove any oil from deep wells around 3000 to 5000 feet in depth, and many wells which should yield a large, 20 profitable flow of oil are practically useless due to the inefficiency of the present type of pumping apparatus.

I have conceived that one of the primary 25 difficulties of the present type of deep well pumps, resides in the failure of the pump to properly draw oil through the bottom valve or standing valve of the pump and that this difficulty may, to a large extent, 30 be overcome by providing a plurality of separate passages of oil controlled by separate standing valves for admitting the oil into the pump proper. In carrying out my invention, I provide a pump having a plurality 35 of separate inlet passages to the pump, each controlled by an independent standing valve and in at least one of the passages provide a separate plunger for drawing the oil through such passages independent of any passage of oil through the other passage.

The invention, and its objects and advantages, will be readily understood from the description of the preferred type or example of the pump embodying the invention, 45 for which purpose reference is made to the accompanying drawings in which such pump is indicated in its preferred form.

In the drawings:

Figure 1 is an elevation of the pump assembled, certain parts being in vertical section.

Fig. 2 is an enlarged elevation, mainly in vertical section, of part of the pump shown in Figure 1.

Fig. 3 is a transverse section on the line 3—3 of Figure 2; and

Fig. 4 is a transverse section on the line 4—4 of Figure 2.

Referring to the drawings, the pump is illustrated as comprising an upper working barrel 2, the lower end of which is threaded to the upper end of a casing 3 which is threaded at a lower point 4 to a casing 5, preferably of a size equal to the size 60 of the working barrel 2. Casing 5 extends downwardly from the casing 3 and provides an inlet to certain parts of the pump, preferably terminating in a slotted section 6 or oil screen. The outer diameter of the casing 3 is preferably equal to the outer diameter of the casing 5 and barrel 2 to provide a smooth exterior surface for the pumping apparatus. The casing 3 provides downwardly and inwardly tapering walls 7 to 70 provide a seat for an outer valve seat member 8. The tapering walls 7 extending throughout the length of the member and below the point 4 where the member is connected with the casing 5. The central portion of the casing 3 is recessed inwardly from the tapering walls 7. Below the point 4 where the casing 3 connects with the casing 5, the casing 3 is provided with a stem 10 of reduced diameter, which, at its lower end, 80 is screwed to an inner or lower working barrel 11 which in turn at its lower end provides a seat for a lower standing valve 12 and is connected to a pipe 13 terminating in a slotted section 14 operating as a screen 85 and inlet line for oil passing to the standing valve 12. The standing valve 12 may be of any preferred or customary construction, being indicated as provided with a ball 15 resting on a valve seat 16 and enclosed 90 by a cage 17 terminating at its upper end in a threaded pin 18.

There is thus provided between the working barrel 11 and the casing 5, an annular chamber or passage 19. This annular passage 19 communicates with the recess 9 in the casing 3 through an annular passage 20 in the casing 3 and which passage 20 extends from the recess 9 to the base of the stem 10 as indicated at 21. Ribs 22 are shown extending across the passage 20 for holding the stem 10 to the remainder of the casing 3.

The outer valve seat member 8 is provided with an annular recess 23 extending inwardly from its exterior which is adapted to 110

register with the recess 9 in the casing 3. Communicating with such recess 23 is an annular passage 24 extending from the upper end of the recess 23 through the top of the outer valve seat member 8, and such passage 24 is normally closed by a ring valve 25, the actual part of the member 8, with which the ring valve 25 engages, is indicated as a separate insert 26 so that the insert 26 may be replaced upon wear without replacing the entire outer valve seat member 8. The valve seat member 8 extends upwardly above the insert 26 as indicated at 27 to provide a guide for the valve 25. Ribs or webs 28 are indicated in Figure 3 extending radially across the passage-way 24 for uniting certain parts of the outer valve seat member 8. The outer valve seat member 8 is provided with a central bore or passage 29 extending from end to end of the member so as to establish communication between the interior of the lower working barrel 11 and the upper working barrel 2. Within the upper working barrel 2 a plunger 30 is mounted to reciprocate. The plunger 30 may be of any preferred or customary type, being indicated as provided with a ball working valve 31 at its upper end and terminating in a pin 32 by which such plunger 30 may be attached to a string of sucker rods, or the like, for reciprocating plunger during the pumping operations. The lower end of the plunger 30 connects with a rod 33 of smaller diameter than the bore or passage 29 through the member 8. Such rod 33 extends through the member 8 and is connected with a plunger 34 of any preferred or customary type which is mounted to reciprocate within the lower working barrel 11, the plunger 34 being provided with a form of working valve 35, indicated as of the ball type.

The operation of the pump mechanism is as follows:

The plunger 30 is reciprocated continually through the working barrel 2, such reciprocation being imparted by the rod 33 to the plunger 34, which thus likewise reciprocates within the working barrel 11. Upon each up-stroke of the plungers 30 and 34 oil, or other fluid in the well, is drawn through the screens 6 and 14, the oil passing only through the screen 6 being drawn up through the passage 19 between the casing 5 and working barrel 11 through the passage-way 20 and recesses 9 and 23 to and through the passage 24 by the ring valve 25 into the lower end of the working barrel 2, the valve 25 being drawn from its seat during this operation. The oil drawn through the screen 14 is drawn by the lower plunger 34, past the ball 15 of the lower standing valve 12 into the lower end of the working barrel 11. Simultaneously, such oil as has been, by a previous down-stroke of the plunger 34 forced above the working valve 35 of such

plunger, is forced upwardly through the bore 29 of the member 8 into the lower end of the working barrel 2.

Upon the downward stroke of the plungers 30 and 34, the ring valve 25 closes the ball 15 of the standing valve 12. The oil above the barrel 12 is pressed against the valve 35 to open such valve and admit the oil there above. The oil above the valve 35 and in the lower end of the working barrel 2 then opens the working valve 31 of the plunger 30 and is admitted above such plunger 30 to be forced upward to the top of the well by succeeding reciprocations of the pump.

By this invention, oil, or other fluid within the well, is found to positively be drawn past the lower standing valves of the pump and the pump may be used with efficiency upon deep oil wells.

While the particular embodiment of the invention herein described is well suited for the purpose of accomplishing the objects of this invention, the invention is not limited to the details of construction of the pump shown, but various modifications may be made without departing from the spirit of the invention. This invention is of the scope set forth in the appended claims.

I claim:

1. A pump of the class described, comprising a working barrel, a plunger in the working barrel, a standing valve below the plunger, an inlet line to the plunger, a working barrel within said inlet line and discharging into the first mentioned working barrel, a second and annular inlet line to said first mentioned working barrel, an annular standing valve for said annular inlet line, and a plunger in said second mentioned working barrel.

2. A pump of the class described, comprising a working barrel, a plunger in the working barrel, a standing valve below the plunger, an inlet line to the plunger, a working barrel within said inlet line and discharging into the first mentioned working barrel, a casing enclosing said second mentioned working barrel and providing an inlet line leading only to said first mentioned working barrel, and annular standing valve for said annular inlet line, a plunger in said second mentioned working barrel, and means connecting the plungers together.

3. In a pump of the class described, a casing the upper portion of which serves as an upper working barrel and the lower portion of which provides an inlet line thereto, an annular standing valve between said two mentioned portions of said casing, an axial opening through said annular standing valve, a casing attached to said annular standing valve and enclosed within the lower portion of said first mentioned casing and providing an annular passage therebetween,

a standing valve closing said inner casing, a plunger within said inner casing, a relatively larger plunger mounted within said first mentioned casing and a rod interconnecting 5 the two plungers.

4. In a pump of the class described, a casing provided with two portions one serving as an upper working barrel and the other of substantially the same diameter serving 10 as an inlet line to said upper barrel, a casing enclosed within said first mentioned casing and providing an annular passage therebetween, an annular standing valve connecting the two portions of said first mentioned

casing and controlling the supply of fluid 15 from the annular space between said first and second mentioned casings into the upper working barrel, said standing valve having an axial opening therethrough, a standing valve for said second mentioned casing, a 20 plunger mounted to reciprocate in said second mentioned casing, and an enlarged plunger mounted to reciprocate in said upper portion of said first mentioned casing, and a rod interconnecting said plungers. 25

Signed at Los Angeles, Cal., this 16 day of May, 1924.

THOMAS W. BRITTAINE.
